UNITED STATES PATENT OFFICE.

FREDERICK MAX PORITZ, OF NEW YORK, N. Y., ASSIGNOR TO STAR CHANDELIER CO., INC., A CORPORATION OF NEW YORK.

DESIGN FOR A BRACKET FOR LIGHTING MEANS.

57,788.

Specification for Design.

Patented May 3, 1921.

Application filed September 18, 1920. Serial No. 411,324. Term of patent 3½ years.

To all whom it may concern:

Be it known that I, FREDERICK MAX PORITZ, a citizen of Germany, having declared my intentions of becoming a citizen of the United States, residing in the borough of Manhattan, city, county, and State of New York, have invented a new, original, and ornamental Design for Brackets for Lighting Means, of which the following is a speci-

fication, reference being had to the accompanying drawing, forming part thereof.

The figure is a perspective view of a bracket for lighting means, showing my new design.

I claim:

The ornamental design for a bracket for lighting means, as shown.

FREDERICK MAX PORITZ.
